UNITED STATES PATENT OFFICE

JOSEPH A. WADDELL, OF WILLIAMSPORT, PENNSYLVANIA, ASSIGNOR TO SPENCER HEATER COMPANY, OF WILLIAMSPORT, PENNSYLVANIA, A CORPORATION OF PENNSYLVANIA

BOILER

Application filed August 6, 1930. Serial No. 473,430.

This invention relates to heaters and has for its object to provide a construction simple in parts, efficient in operation, and less costly to manufacture than those heretofore proposed.

With these and other objects in view the invention resides in the novel details of construction and combinations of parts as will be disclosed more fully hereinafter and particularly pointed out in the claims.

Referring to the accompanying drawings forming a part of this specification in which like numerals designate like parts in all the views,

Fig. 1 is a front elevational view of a complete heater made in accordance with this invention;

Fig. 2 is a general longitudinal vertical sectional view illustrating the interior construction of the heater;

Fig. 3 is a vertical sectional view taken transversely of the heater;

Figs. 4, 5, 6 and 7 are diagrammatic perspective views illustrating steps in the assembly of the heater;

Fig. 8 is a perspective view of the inner face of the back section of the heater;

Fig. 9 is a perspective view illustrating the construction on the inner side of the front section of the heater;

Fig. 10 is an elevational view of the parts shown in Fig. 9;

Fig. 11 is a fragmentary horizontal view showing the construction at a corner of the heater and taken for example as on the line 11-11 of Fig. 3 and looking in the direction of the arrows;

Fig. 12 is a general transverse vertical sectional view of a modified form of heater made in accordance with this invention; and

Fig. 13 is a plan of the grate assembly.

This heater is of a type adapted either for hot water or steam systems and comprises a construction of the magazine feed type wherein a compartment may be filled with coal or other suitable fuel which automatically feeds downwardly, under the urge of gravity, to the grate. Also this heater is somewhat similar to the sectional magazine feed type heaters heretofore known, in gen-

eral lines of construction, but it differs therefrom in that this heater is made of sheet metal to reduce the manufacturing costs, and is not made in sections as commonly understood and whereby heaters of differing depths may be formed by the omission or addition of intermediate sections. This heater, however, does include an assemblage of water jackets formed by spaced sheet metal plates, and pipes or tubes extending from the front to the back of the heater. Also the present construction provides for an inclined grate, the highest point of which is immediately below the throat of the fuel magazine so that the fuel from the latter upon reaching the grate will gradually slide or move thereover, as it is being consumed, to the lowest portion of the grate where substantially nothing but ash remains.

With particular reference to Figs. 4 to 10, it is believed that the general construction of this heater may be readily understood. There is provided a continuous sheet metal plate which is of a length that it may be circularly bent around to provide a main body portion 1 constituting the outer left wall of the heater and a shorter portion 2 constituting one wall of the fuel magazine, the portion 2 being substantially parallel to the main body portion but spaced therefrom to provide room for a plurality of flue pipes. The extreme end portion 3 of that part of the plate which is bent around is deflected out of the plane of the portion 2 and in a direction away from the main body portion 1, to form one side of the constricted throat of said magazine, the extreme end edge 4 of the portion 3 being disposed not quite one half the distance from the top 5 of the curved portion of the plate to the other end engaging end edge 6 at the bottom of the main body portion. By way of example only and in order that some idea of relative size of this heater may be had the vertical dimension of this peculiarly formed sheet, from the base edge 6 to the top 5 of the curved portion, is approximately 5 feet; the spacing of the portion 2 from the main body portion 1 is approximately 14 inches; the horizontal distance from the end 4 of the sheet to the main body

100

portion 1 is approximately 20 inches; and the vertical distance of the edge 4 below the top 5 of the curved portion is approximately 26 inches.

5 A second continuous plate comprising a main body portion 10 has one end provided with substantially a quarter bend so that when the adjacent end edge 11 is welded to the inner surface of the main body portion 1 of the aforementioned plate, the main body 10 and 1 will be parallelly spaced approximately two inches from each other, the main body portion 10 constituting one wall of the combustion chamber. Said second 15 plate is rectangularly bent to provide, adjacent the main body portion 10, a section 12 which ultimately forms the floor of the main water chamber of this heater, as well as the roof of the combustion chamber. The portion 12 extends horizontally to a point near the bend between the sections 2 and 3 of the aforementioned plate, at which point said second plate is bent to provide a downwardly and inclined section 13 which is parallelly 20 spaced substantially two inches from the section 3 of the other plate, the end portion of the section 13 having a quarter circular bend to bring its extreme edge 14 in position to be welded to the edge 4 of the other plate. 25 30 From the foregoing it will thus be seen that the left side of this heater is formed by two metallic plates each bent and both joined by welding to produce a space 15 between the major portions thereof which space ultimately becomes a water leg in the completely assembled heater. Said plates are further assembled to provide the domed space 16 which ultimately becomes the main water chamber of said heater; and said sheets are still further disposed to provide the space 17 which 35 ultimately becomes the water jacketed throat of the fuel magazine. For the purpose of example only, the lower joint between the two plates 1 and 10 is made substantially 11 inches 40 above the floor.

45 During assemblage and in order to rigidly maintain spacing, spacers such as 20 are welded between the main body portions 1 and 10, as well as between the sections 3 and 13. 50 Also a plurality of vertical spacing rods 21 are disposed between the top 5 and the bottom 12 of the domed water chamber 16, and a plurality of horizontally disposed reinforcing rods 22 are rigidly secured between 55 the main body portion 1 and the section 2 of the outer plate (see Fig. 3).

60 The right side of this heater comprises two welded continuous plates 23 and 24, spaced from each other to provide therebetween a second water leg 25, see Fig. 5. The outside plate 23 rests vertically upon the floor, is perfectly plane, and of a length substantially equal to the vertical distance between the floor and the bottom wall 12 of the water chamber. 65 The inside plate 24 parallel to the plate 23,

has each opposite end portion provided with a quarter circular bend with the extreme edges 26 and 27 welded or otherwise secured to the plate 23, the edge 27 being secured at or closely adjacent to the top edge 28 of the plate 23, and the lower edge 26 being approximately 70 21 inches from the floor. Similar reinforcing spacers 20 are provided between the plates 23 and 24, the plate 23 forming a portion of the wall of the fuel magazine as well as the 75 other side of the constricted throat thereof.

The left and right sides of the heater are joined at the top by a bent plate, the bend having the same radius of curvature as that used to produce the curved dome 5 of the water chamber 16, and the plate so dimensioned and formed as to provide, adjacent the bend, a section 30 whose edge 31 is abuttingly welded to the top edge 28 of the plate 23, and another section 32 whose edge 33 is welded to the top 80 surface of the dome of the water chamber 16. The section 30 is disposed in the plane of the plate 23 and forms the upper side of the fuel magazine, while the section 32 forms the horizontal roof of said magazine as well as the 85 major portion of the roof of the heater. In the completely assembled heater the left and right sides will be parallel to each other with a spacing of substantially six inches between the edge 4 of the throat of the fuel magazine 90 and the inner plate 24 of the water leg 25. Up to this point the foregoing description covers the assemblage of the heater to produce the construction shown in Fig. 6; there being 95 provided on the inner face of the plate 1 a plurality of brackets 35, and on the inner face of the opposite plate 23 a plurality of brackets 36 which are disposed below the water legs 100 for the purpose of supporting the grate assembly. 105

110 The front of the heater comprises a continuous plane plate indicated by the numeral 40, see Figs. 9 and 10, provided near the top with an aperture 41 adapted to register with the main portion of the fuel magazine and through which said magazine is charged. A second aperture 42 is provided substantially half way down the plate 40 and adapted to register with the combustion chamber, and at the bottom of the plate is a third opening 43 adapted to provide access to the ash pit. The edges of the plate 40 are of a contour designed 115 to register with the side edges of the plates 1, 23 and 30 and to be welded thereto, but here it should be stated that the inner plates 10 and 24 are not of the same width as their associated plates 1 and 23 respectively. In other words, the inner plates are narrower, and are positioned to have their vertical edges 120 stepped back substantially two inches from the adjacent and corresponding edges of their associated outer plates. The purpose of this is to provide a ready means for welding the 125 vertical edges of said inner plates to the 130

inner plates associated with the front and back sections of the heater.

That is to say, the front plate 40 has a narrower plate 44 secured thereto and separated 5 therefrom as by the spacers 20, the plate 44 being so spaced that its vertical side edges will register for welding with the vertical edges of the inner side plates 10 and 24. In order that this construction may be understood more clearly, it is stated that the vertical edge 45 of the plate 44 is stepped back about 2 inches from the corresponding edge of the plate 40 and welded to the vertical edge of the inner side plate 24, and 10 the other opposite vertical edge 46 of said plate 44 is likewise stepped back and welded to the vertical edge of the inner side plate 10, it being understood, of course, that the side edges of the plate 40 will also be welded to 15 the edges of the outer side plates 1 and 24.

The plate 44 is of irregular form or contour which will be more readily understood from the figures of drawings than from any description that can be written, but it might 20 be particularly stated that it has a lower oblique section which has the same inclination as that of the grate in order that the front wall of the combustion chamber and the grate will be water jacketed. A fourth 25 opening 47 is provided in the plate 40 just above the opening 42 for the purpose of cleaning out the interior flue space in the assembled heater, and around the opening 47 there is welded a narrow sheet metal strip 48 substantially 2 inches in width, a similar strip being provided around the opening 42, along the top of the plate 44 and along the bottom edge thereof, said strips being welded in 30 place whereby it will be seen there is provided a closed water jacket space between the plates 40 and 44 when the heater is assembled. The inner plate 44 has an opening 49 therethrough adapted to register with the lower portion of the space 17 of the jacketed 35 magazine throat, whereby water may pass between said throat jacket and the water jacket of the front of the heater, it being understood that the edges of the wall sections 12 and 13, forming the top of the combustion chamber, as well as the edge of the 40 wall section 3 forming one side of the fuel magazine throat, will be welded to the exposed surface of the plate 44.

The rear of the heater comprises a continuous plane plate 50 of the same contour as the front plate 40, said plate being provided in its lowermost portion with an opening 51 giving access to the ash pit. Joined to the plate 50 as by spacers 20 is an inner narrower plate 52 so spaced that the vertical edges of the inner plate will readily register with the rear vertical edges of the inner side plates 10 and 24. That is to say, the vertical edge 53 of the plate 52 is welded to the vertical edge of the inner plate 24 of the right

side of the heater, while the opposite vertical edge 54 is welded to the rear vertical edge of the inner plate 10 of the left side of the heater. The lower edge of the plate 52 is formed obliquely in accordance with the slope of the grate to provide at the rear wall of the heater a water jacket adjacent the grate. The plate 52 has along its upper and lower edges narrow strips of sheet metal substantially two inches in width, similar to the strip 48 shown in Fig. 9, said strips welded in place between the plates 50 and 52 so as to form a water jacket on the rear wall of the assembled heater. An aperture 55 is provided in the plate 52 similar to the aperture 49 and also furnishing communication between the rear water jacket and the jacketed magazine throat. The edges of the outer rear plate 50 are welded to the rear edges of the plates 1, 24 and 30, the edges of the inner wall sections 3, 12 and 13 are welded to the exposed surface of the rear inner plate 52, and the opposite edges of the wall section 2 are welded to the inner surfaces of the front and rear outer plates 40 and 50.

A plurality of substantially parallel and horizontal flue pipes 60 extend through the water chamber 16 with their opposite ends welded into suitable openings 61 and 62 in the front and rear plates 40 and 50 respectively, and a plurality of water conducting pipes 63 extend between the front and rear water jackets, having their ends welded in suitable openings 64 and 65 in the inner water jacket plates 44 and 52 respectively, the pipes 63 being slightly inclined upwardly at the rear. A baffle plate 66 is disposed over the water pipes 63 between the side plate 10 and the wall section 13 of the magazine throat jacket, said baffle joined to the plate 44 and extending substantially two-thirds the distance between the front and rear water jackets, whereby the gases of combustion will pass from the burning fuel upwardly and rearwardly, thence around the free end of the baffle plate 66, thence forwardly under the water chamber 16, thence rearwardly through the flue pipes 60, and out of the heater through the stack connection 67 provided with a damper 68 and secured to the rear of the heater. (See Fig. 2.)

The grate may be of any suitable construction but preferably comprises a rectangular frame made of angle irons, the front and back irons 70 and 71 respectively having their flanges uppermost to serve as ledges for the fuel against the front and rear water jackets (see Fig. 2), while the side irons have their flanges reversed (see Fig. 3) to permit the frame to fit the heater. That is to say, this heater is of the fuel magazine type with a grate inclined downwardly from the magazine side, and hence the frame for the grate is disposed obliquely across the heater. The angle iron 72 forming the left and lower side

of the grate frame has its flange at the bottom to rest on the supporting brackets 35 while the upper web edge of said iron will just clear the inner water leg plate 10. On the other hand, the angle iron 73 forming the right and upper side of the grate frame has its lower web edge resting on the supporting brackets 36, and its flange at the top just clearing the inner water leg plate 24, as a result of which said flange offers a solid smooth surface upon which the fuel from the magazine falls and slides from in the natural direction of the grate.

The inner face of the frame iron 72 has secured thereto a plurality of lugs 74, and the inner face of the opposite frame iron 73 has secured thereto a plurality of plates each provided with an upwardly opening pocket 75, the lugs and pockets being opposed to each other and spaced to receive opposite ends of grate sections. Each grate section preferably comprises a hollow tube or pipe 76 supportedly fitting a lug and its opposed pocket, said tube having mounted thereon two grates 77 and 78 adapted to be rocked by the shaker bars 79 and 80 respectively, which bars extend through twin slots 81 in the front outer plate 40 and are pivotally connected to well known twin cranks indicated at 82 in Fig. 1 operable by the usual hand shaker levers not shown.

At the top of the water chamber in the plate 1 there is provided a pair of openings such as 83 connected to the steam service pipes 84 and 85, and across the upper region of the water chamber 16 just below each of these openings are baffles 86 and 87 to prevent entry of water into the steam service pipes, said baffles welded in place. A steam gauge 88, as well as a pressure draft regulator generally indicated by the numeral 89 are also connected to the domed water chamber 16. The return service pipe 90 is connected to the rear plate 50 at the water jacket thereof. Drain or clean out plugs 91 are tapped into the front and rear plates 40 and 50 at convenient and appropriate locations, doors are provided to close the openings 41, 42, 43, 47 at the front, and a draft damper casting 92 is provided at the rear to close the opening 51.

The modification illustrated in Fig. 12 shows a double heater of substantially the same type of construction in that sheet metal plates are utilized to form the walls of the heater, the only difference being in the formation of the water chamber and jacketed magazine throat. That is to say the right side of this modified heater comprises an assemblage of plates 100 and 101 of the same shape and dimensions as the plates 23 and 24 heretofore described. To the top edge of the plate 100 is welded a curved plate 102 which is a substantial duplicate of the aforementioned plate 30. The left side of the heater comprises an assemblage of plates 103, 104, and 105 which are exact duplicates of the

plates 100, 101, and 102 except that they are reversely formed, as will be understood. Both the left and right sides have attached to their outer plates a plurality of brackets 106 which are the duplicates of the brackets 70 illustrated in Fig. 3.

The water chambers of this double heater are disposed centrally thereof and have a construction slightly different from that of the water chamber heretofore described. In other words, there is provided on the right hand half of the double heater a plate which is provided with a plurality of bends and which extends from the weld joint 107 to the weld joint 108 and which includes a central vertical section 109, a horizontal section 110 which ultimately forms the floor of the water chamber 111 as well as a portion of the roof of the combustion chamber 112, and a downwardly and outwardly inclined section 113 which forms one side wall of the water jacket 114 associated with the throat of the fuel magazine 115. A second plate extends from the weld joint 107 to the weld joint 108 and which is provided with a plurality of bends to form the other vertical side wall section 116 of the water chamber 111, and the section 117 which is parallel to the section 113 and forms therewith the other wall of the water jacket 114, spacers such as 20 being provided to reinforce and maintain the rigidity of said water jacket. The plate 102 is welded to the wall of the water chamber as at the point 118.

In a similar manner but in reverse formation plates are provided in the left side of the double heater to provide the companion water chamber 120. In other words, on the left side of this heater there is a plate extending from the weld joint 121 to a second weld joint 122 and which includes a vertical wall section 123 adapted to contact the wall section 109 of the water chamber 111, a section 124 which lies in the same horizontal plane with the section 110, and an oblique section 125 symmetrical with the section 113. A second plate extends between the weld joints 121 and 122 and has the vertical section 126 forming the other side of the water chamber 120, and the oblique section 127 parallel to and separated as by the spacers 20 from the oblique section 125 to form therebetween the water jacket 128 associated with the throat of the fuel magazine 129 on the left side of the heater.

Extending from the front section to the rear section through the water chambers 111 and 120 are flue pipes similar to the pipes 60, and below the water chambers and between the water jacketed throats of the fuel magazines is provided a plurality of water conducting pipes similar to the pipes 63, with a baffle 135 extending thereover. The front and rear sections of this heater are formed similarly to the front and rear sections of

the single heater hereinbefore described, except as to size. At the floor line of the double heater and centrally thereof, is a plate 136 disposed vertically and extending from the front section to the rear section, and to the top of this plate is suitably secured a casting 137 having formed on its opposite sides lugs such as indicated at 138 adapted to receive one end of a grate member generally indicated by the numeral 139, the opposite end of which is dropped into a pocket such as 140 formed on the angle iron 141 resting upon the brackets 106. The casting 137 is disposed a substantial distance below the brackets 106 whereby the grate sections 139 are given inclinations downwardly from the sides of the the heater, as a result of which fuel from the magazines 115 and 129 will drop upon the elevated ends of the grates, and slide thereover in a direction toward the center of the heater while being consumed.

Thus it will be seen from the foregoing, that there is provided a heater of the magazine feed type which comprises four outer walls 1, 24, 40 and 50 each formed by a plate of sheet metal, a top formed by an extension 5 of one of the outer walls and another plate 30 joining said extension with the opposite side wall 24, said extension 5 continued interiorly of said heater to form one side 2 of a fuel magazine, the edges of said walls and said top welded to provide a closed casing, an inner plate (10, 23, 44, 52) secured in spaced relation to each plate of the outer wall the vertical edges of the inner plates welded to provide a continuous combustion chamber wall, one of the inner plates 10 extended and joined to the interior end 4 of the extended outer plate (1) to provide therebetween a water chamber 16, and the lower edges of said inner plates joined to the outer plates to provide water legs and water jackets or headers communicating with the water chamber, the joined outer walls constituting the outer shell and the joined inner walls providing an inner shell, the vertical edges of the inner plates being stepped back from the corresponding edges of the outer plates to facilitate in the assemblage and welding of the plates to form the heater.

It is obvious that those skilled in the art may vary the details of construction and arrangement of parts without departing from the spirit of the invention, and therefore it is not desired to be limited to the foregoing except as may be desired by the claims.

What is claimed is:—

1. A heater of the magazine feed type comprising outer plates of sheet metal welded at their edges to provide the outer casing of the heater, one of said plates extended downwardly interiorly of the casing to form one wall of the magazine; inner plates of sheet metal secured to said outer plates in spaced relation the edges of said inner plates welded

together to provide water jackets on the front and rear and water legs on the opposite sides of the heater, one of said inner plates extended inwardly and downwardly interiorly of the extended outer plate to form therewith a water chamber at the top of the heater and an oblique downward extension thereof constituting a water jacketed constricted throat at the bottom of the magazine; tubes extending from the front to the rear their ends supported by opposite outer and opposite inner plates, said tubes constituting respectively flues, and water conducting passages the former passing through said water chamber and the latter communicating with said water jackets; an inlet and an outlet for conducting fluid to and from the heater; an inclined grate disposed between the lower extremities of said water legs; and draft openings in the outer plates.

2. A heater of the magazine feed type comprising outer plates of sheet metal welded at their edges to provide the outer casing of the heater, one of said plates extended downwardly interiorly of the casing to form one wall of the magazine; inner plates of sheet metal secured to said outer plates in spaced relation the edges of said inner plates welded together to provide water jackets on the front and rear and water legs on the opposite sides of the heater, one of said inner plates extending inwardly and downwardly interiorly of the extended outer plate to form therewith a water chamber at the top of the heater and an oblique downward extension thereof constituting a water jacketed constricted throat at the bottom of the magazine, said chamber extension in open communication with said water jackets; tubes extending from the front to the rear their ends supported by opposite outer and opposite inner plates, said tubes constituting respectively flues and water conducting passages the former passing through said water chamber and the latter communicating with said water jackets; an inlet and an outlet for conducting fluid to and from the heater; an inclined grate disposed between the lower extremities of said water legs; and draft openings in the outer plates.

3. A heater of the magazine feed type comprising outer plates of sheet metal welded at their edges to provide the outer casing of the heater, one of said plates extended downwardly interiorly of the casing to form one wall of the magazine; combustion chamber forming inner plates of sheet metal secured to said outer plates in spaced relation the edges of said inner plates welded together to provide water jackets on the front and rear and water legs on the opposite sides of the heater, one of said inner plates extended inwardly and downwardly interiorly of the extended outer plate to form therewith a water chamber at the top of the heater and an oblique

downward extension thereof constituting a water jacketed constricted throat at the bottom of the magazine; tubes extending from the front to the rear their ends supported by 5 opposite outer and opposite inner plates, said tubes constituting flues and water conducting passages the former passing through said water chamber and the latter passing through the upper portion of the combustion chamber 10 and communicating with said water jackets; an inlet and outlet for conducting fluid to and from the heater; an inclined grate disposed between the lower extremities of said water legs; and draft openings in the outer 15 plates.

4. A heater of the magazine feed type comprising outer plates of sheet metal welded at their edges to provide the outer casing of the heater, one of said plates extended downwardly interiorly of the casing to form one 20 wall of the magazine; inner plates of sheet metal secured to said outer plates in spaced relation the vertical edges of said inner plates stepped back from the corresponding 25 edges of the outer plates and welded together to provide water jackets on the front and rear and water legs on the opposite sides of the heater, one of said inner plates extended inwardly and downwardly interiorly of the 30 extended outer plate to form therewith a water chamber at the top of the heater and an oblique downward extension thereof constituting a water jacketed constricted throat at the bottom of the magazine; tubes extending 35 from the front to the rear their ends supported by opposite outer and opposite inner plates, said tubes constituting respectively flues and water conducting passages the former passing through said water chamber and the latter communicating with said water jackets; an inlet and an outlet for conducting fluid to and from the heater; an inclined 40 grate disposed between the lower extremities of said water legs; and draft openings in the outer 45 plates.

5. A heater of the magazine feed type consisting of an outer shell and an inner shell, each shell formed by plates of sheet metal welded along their edges one of the plates 50 of the outer shell having a portion bent parallel to the major portion, the bent portion extending interiorly and forming one wall of the magazine, the plates of the inner shell secured in spaced relation to the plates of the outer shell by a plurality of interposed spacers, the shells forming therebetween water 55 compartments, tubes constituting flues disposed between the major and bent portions of said outer plate, and an inlet and an outlet communicating with said compartments through the outer shell.

6. A heater of the magazine feed type consisting of an outer shell and an inner shell, each shell formed by plates of sheet metal 60 welded along their edges one of the plates 65

of the outer shell extending interiorly and forming with other plates of said outer shell the fuel magazine, the plates of the inner shell secured in spaced relation to the plates of the outer shell by a plurality of interposed spacers, the shells forming therebetween water compartments, tubes constituting flues disposed between said one of the outer plates and its extension, and an inlet and an outlet 70 communicating with said compartments through the outer shell. 75

7. A heater comprising four outer walls each formed by a plate of sheet metal; a top formed by an extension of one of the outer walls and another plate joining said extension with the opposite side wall said extension continued interiorly of said heater to form one side of a fuel magazine; the edges of said walls and said top welded to provide a closed casing; an inner plate secured in spaced relation to each plate of the outer wall, the vertical edges of the inner plates welded to provide a continuous combustion chamber wall; one of the inner plates extended and joined to the interior end of the extended outer plate to provide therebetween a water chamber; tubes disposed above and below said last mentioned inner plate forming respectively flues and water conducting passages; and the lower edges of said inner 85 plates joined to the outer plates to provide water legs and water jackets communicating with said water chamber. 90

8. A heater comprising an inclined grate disposed between four outer walls each wall 100 formed by a plate of sheet metal, a top formed by an extension of one of the outer walls and another plate joining said extension with the opposite side wall said extension continued interiorly of said heater to 105 form one side of a fuel magazine, the edges of said walls and said top welded to provide a closed casing, an inner plate secured in spaced relation to each plate of the outer wall, the vertical edges of the inner plates welded to provide a continuous combustion chamber wall, one of the inner plates extended and joined to the interior end of the extended outer plate to provide therebetween a water chamber, and the lower edges of said 110 inner plates joined to the outer plates to provide water legs and water jackets communicating with said water chamber the water legs being of different lengths and terminating at the top of the grate. 115

9. A heater comprising four outer walls each formed by a plate of sheet metal; a top formed by an extension of one of the outer walls and another plate joining said extension with the opposite side wall said extension continued interiorly of said heater to form one side of a fuel magazine; the edges of said walls and said top welded to provide a closed casing; an inner plate secured in spaced relation to each plate of the outer 125 130

wall, the vertical edges of the inner plates welded to provide a continuous combustion chamber wall; one of the inner plates extended and joined to the interior end of the extended outer plate to provide therebetween a water chamber; tubes disposed above and below said last mentioned inner plate forming respectively flues and water conducting passages; and the lower edges of said inner plates joined to the outer plates to provide water legs and water jackets communicating with said water chamber the water legs terminating at their lower ends in different horizontal planes and meeting the top of the grate.

10 10. A sheet metal boiler of the magazine feed type including a water chamber provided with an outlet, a fuel magazine to one side of the water chamber, an inclined hollow extension communicating with and depending from the chamber to form at one side a combustion chamber and at the other side a constricted fuel outlet from the magazine, front and rear headers one of the headers 20 having a water inlet, a water passage from the header into the end of the extension, and a water leg connecting the headers, sheet metal end plates forming the end walls of the water chamber, and the headers, side 25 plates forming the outer side walls of the water leg and headers united to the end plates, plates forming the inner walls of the headers and water leg united to one another and to the end and side plates, sheet metal 30 plates forming the outer side walls of the water chamber and its extension formed of plates welded together and welded at their ends to the end plates 35 and to the inner walls of the headers.

11. A heater provided with a fuel magazine and including a water chamber at the top of the heater, water legs on opposite sides of the heater, and water jackets on opposite ends of the heater, all in open communication with each other and formed by 40 plates of sheet metal welded together at their edges, one side of said chamber constituting a division wall between said chamber and the fuel magazine; and tubes terminating in the end plates, some of said tubes constituting 45 flues passing through said water chamber, and the other of said tubes constituting water-conducting passages joining said water jackets.

12. A heater of the magazine feed type consisting of an outer shell and an inner 50 shell, each shell formed by plates of sheet metal welded along their edges one of the plates of the outer shell having a portion bent parallel to the major portion, the bent portion extending interiorly and forming the inner wall of the magazine, the plates of the inner shell secured in spaced relation to the plates of the outer shell by a plurality of interposed spacers, the shells forming therebetween water compartments, tubes constituting flues disposed between said inner mag-

azine wall and one of the plates of the outer shell, and an inlet and an outlet communicating with said compartments through the outer shell.

In testimony whereof I affix my signature. 70
JOSEPH A. WADDELL.
